ATOMIZER CONTROL

Joy B. Schmitt, Toledo, Ohio, assignor to The De
Vilbiss Company, Toledo, Ohio, a corporation of
Ohio

Application August 10, 1933, Serial No. 684,597

3 Claims. (Cl. 299—88)

This invention relates to spraying devices of the type commonly used for the spraying, in atomized form, of toilet and other liquids, and particularly to those having valves operable to 5 tightly close the passages leading from the liquid receptacles to prevent leakage of liquid from the receptacles should they be placed in other than upright position.

The invention relates particularly to improvements on the atomizer control disclosed in United States Letters Patent No. 1,897,679, issued February 14, 1933.

The primary object of the invention is the provision of means in a control of the type disclosed in said patent, whereby the valve is automatically opened and maintained open by pneumatic pressure present in the atomizer when and only when it is being treated to discharge material therefrom.

The invention is fully described in the following specification, and while in its broader aspect it is capable of embodiments in numerous forms, one embodiment thereof is illustrated in the accompanying drawing, in which—

Figure 1 is a central vertical section of a device embodying the invention, with parts in full, and showing the valve means in normal liquid passage closing position, and Fig. 2 is a section of the device taken on the line 2—2 in Fig. 1.

Referring to the drawing, 1 designates the liquid receptacle of an atomizer or spraying device embodying the invention, the neck 2 of which is closed by a spray-head 3 attached thereto in the usual or any suitable manner.

The spray-head 3 has the customary spray nozzle 4 provided with a mixing chamber 5 and discharge orifice 6 therefrom, and having air and liquid discharge passages 7 and 8, respectively, leading into said chamber. The liquid passage 8 leads into the side of a bore or passage 9 provided axially in the spray-head. The lower end of the bore 9 opens into an enlargement 10 provided in the lower end portion of the head 3, and a plug or bushing member 11 is threaded into the lower end of this enlargement and cooperates with the enlargement 10 to form a valve chamber. The upper end of the bushing 11 forms an annular valve-seat 12, while the upper end wall of the enlargement 10 forms an annular valve-seat 13. The upper end of the bore 9 has a reduced axial extension 14 opening at its top centrally into the bottom portion of a recess 15 provided in the upper end of the head 3.

A valve-stem 16 is mounted for reciprocatory movements in the bore extension 14 and extends

at its upper end into the recess 15 and at its lower end down through the bore 9, the valve 10 and bushing 11. The stem 16 has a valve enlargement 17 within the chamber 10 and this enlargement is provided with two opposed conical faces one adapted to seat against the valve-seat 13 when the stem is raised, and the other being adapted to seat against the valve-seat 12 when the stem is lowered within the spray-head. A spring 18 acts on the valve-stem within the recess or chamber 15 and normally holds the valve-stem in raised position with the valve enlargement 17 seating against the seat 13, thus normally closing the communication between the valve chamber 10 and the bore 9 into which the liquid discharge passage 8 opens.

The lower end of the valve-stem 16 projects freely down through the bushing 11 and carries a tube 19, which extends down to near the bottom of the receptacle 1 with its lower end in submerged relation with the liquid therein, as well understood in the art. The passageway in the tube 19 communicates at its upper end with a passageway 20 disposed axially for a distance in the stem 16 and having its upper end communicating with the interior of the chamber 10 between the two seating faces of the valve enlargement 17.

A plunger 21 is mounted in the outer end of the head recess 15 and bears on the outer end of the stem 16, so that an inward pressure exerted on the plunger will impart movement to the stem against the pressure of the spring 18 and will cause the valve 17 to lower and effect an opening of the communication between the chamber 10 and bore 9 and to close communication between said chamber and the upper interior portion of the receptacle 1 around the valve-stem through the bushing 11.

A cap 22 is mounted on the upper end of the spray-head 3, being threaded thereon in the present instance, and cooperates with the upper end of the head and the plunger 21 to form a chamber 23. The air passage 7 is angled and opens at its inner end into the chamber 23, and an air supply passage 24 also opens into said chamber at one end and has communication at its opposite end through a tube 25, or other suitable connection, with a source of air pressure supply of any suitable type, as, for instance, a hand-operated compression bulb. It is thus apparent that the communication between the air pressure supply source and the air discharge tube 7 of the nozzle is through the chamber 23, so that pressure therein is exerted on the plunger 21 against the tension

of the spring 18. The tension of such spring is so regulated that when the air pressure is sufficient for operating the atomizer to effect a spraying of liquid therefrom, it will also be sufficient to lower 5 the valve-stem to unseat the valve with respect to the seat 13 and seat it with respect to the seat 12. It will be understood, of course, that this movement of the valve takes place before the spraying action, as the latter is dependent on the 10 opening of the communication between the chamber 10 and bore 9 and the closing of the communication between said chamber and the receptacle through the bushing 11. A passage 26 is provided between the inner end of the recess 15 and the atmosphere through the head 3 to form an air vent for said recess at the inner side of the plunger.

In the use of the device, the liquid discharge 20 passage 8 is normally closed to the valve chamber 10 and to the interior of the liquid receptacle by the seating of the valve 17 against the valve-seat 13, due to the action of the spring 18. When air under pressure is supplied to the air discharge 25 passage 7 through the air chamber 23 to effect an operation of the atomizer, it first acts on the plunger 21 to lower the valve-stem 16 to effect an opening of the communication between the chamber 10 and liquid discharge passage 8 and incidentally to effect a seating of the lower face 30 of the valve against the seat 12, which latter closes communication between the chamber 10 and the interior of the receptacle except through the stem passage 20 and tube 19. Should the air within the receptacle, when the device is not in 35 use, become expanded, for instance by reason of setting in the sun, the pressure thus created enters the chamber 10 through the space between the bushing 11 and valve-stem and enters the stem passage 20, thus partially equalizing the 40 pressure of the air on the liquid within and without the stem and tending to prevent the liquid from being forced into the chamber 10. When the valve-stem is depressed, communication between the chamber 10 and discharge passage 8 is 45 open, thereby relieving the air pressure within the chamber 10 and also momentarily from the interior of the receptacle until the valve has been lowered sufficiently to seat against the valve-seat 12. The movement of the valve between 50 the two seats is not very great, but it is found that it is adequate to sufficiently relieve the air pressure within the receptacle during the downward movement of the valve from closed to full-opened position to prevent liability of the liquid within the receptacle being forced out of the spray-head by such air pressure.

The construction and operation of the present device is the same as that of the device in the above-mentioned Patent 1,897,679, with the exception that in the patent the valve and its stem 60 are manually lowered from normal seating position, whereas, in the present case, the lowering of the valve is automatically effected by pneumatic action, due to pressure in a part of the head when the atomizer is being operated to effect a spraying 65 action. This is an important change over

the construction of said patent, inasmuch as it makes the opening of the valve entirely automatic and relieves the operator of such action.

I wish it understood that my invention is not limited to any specific arrangement or form of the parts, as it is capable of numerous modifications and changes without departing from the spirit of the claims.

Having thus described my invention, what I claim as new, and desire to secure by United States Letters Patent, is:

1. In a hand portable and operated atomizer for spraying liquids, a container having an opening in its top, a head mounted on said container in closing relation to its opening, a discharge nozzle on one side of said head, an air pressure supply connection attached to a side of the head in angularly spaced relation to said nozzle, said head having a top portion with a plunger receiving chamber therein having an open upper end, a closure for the upper end of said chamber, said head also having a liquid supply passage extending from the bottom portion of the receptacle through the opening thereof to said nozzle and having an air passage leading from said air supply connection to the top of said chamber and a smaller air passage leading from the top of said chamber to said nozzle, a plunger in said chamber with one side exposed to the top of the chamber, a valve in and normally closing said liquid supply passage, and means responsive to air pressure in the top of said chamber to open said valve when a predetermined air pressure is present in said chamber and subsequent to the initial discharge of air from the nozzle.

2. In a hand portable and operated atomizer for spraying liquids, a liquid container, a head mounted on the container, a discharge nozzle on one side of the head, said head having an air passage leading from an air pressure supply source to said nozzle and a liquid passage leading from the bottom portion of the receptacle to said nozzle, a valve normally closing said liquid passage, and means acted on by air in its passage through the air passage to said nozzle and subsequent to its initial discharge from the nozzle to effect an opening of said valve when a predetermined pressure is present in the nozzle.

3. In a hand portable and operated atomizer for spraying liquids, a liquid container, a head mounted on the container, a discharge nozzle on one side of the head, said head having a plunger receiving chamber in its upper portion, an air supply passage leading from a source of air supply through said chamber to said nozzle with its outlet from the chamber restricted relative to its inlet and having a liquid passage leading from the interior bottom portion of the receptacle to said nozzle, a valve in and normally closing said liquid passage, and a plunger in said chamber having operating connection with the valve down through a portion of the head, said plunger being responsive to predetermined air pressure in said air passage to open said valve.

JOY B. SCHMITT.
